US00D981662S

(12) **United States Design Patent** (10) **Patent No.:** **US D981,662 S**
(45) **Date of Patent:** **** Mar. 21, 2023**

(54) **MASK CLEANING DEVICE**

(71) Applicant: **Cleanbox Technology, Inc.**, Carlsbad, CA (US)

(72) Inventor: **David Allen Georgeson**, Vista, CA (US)

(73) Assignee: **Cleanbox Technology, Inc.**, Nashville, TN (US)

(**) Term: **15 Years**

(21) Appl. No.: **29/732,754**

(22) Filed: **Apr. 27, 2020**

(51) **LOC (14) Cl.** **15-05**

(52) **U.S. Cl.** **USPC** **D32/1**

(58) **Field of Classification Search**

(57) **CLAIM**

The ornamental design for a mask cleaning device, as shown and described.

DESCRIPTION

FIG. 1 is a top perspective view of a mask cleaning device showing the new design.

FIG. 2 is a bottom perspective view thereof.

FIG. 3 is a front view thereof.

FIG. 4 is a rear view thereof.

FIG. 5 is a top view thereof.

FIG. 6 is a bottom view thereof.

FIG. 7 is a right side view thereof; and,

FIG. 8 is a left side view thereof.

The “CLEANBOX” forming part of the claimed design disclosure is a registered trademark of the CleanBox Technology, Inc.

The portions of the mask cleaning device shown in broken line form no part of the claimed design.

1 Claim, 5 Drawing Sheets
